Heremach Fiske

UNITED STATES PATENT OFFICE.

JEREMIAH FISK, OF AUGUSTA, MAINE.

IMPROVEMENT IN SPRING-BED.

Specification forming part of Letters Patent No. 92,949, dated July 27, 1869.

To all whom it may concern:

Be it known that I, JEREMIAH FISK, of Augusta, in the county of Kennebec and State of Maine, have invented an Improved Spring for Beds, Upholstery, and other purposes; and I do hereby declare that the following, taken in connection with the drawings which accompany and form part of this specification, is a description of my invention sufficient to enable those skilled in the art to practice it.

This invention consists in a spring of novel arrangement and construction, which is used most advantageously in numbers placed side by side, and connected in pairs or in greater numbers.

The drawings exhibit my spring as applied to a bed for the support of a mattress, Figure 1 showing said spring in side elevation, and Fig. 2 in plan, parts of the bedstead also showing incidentally in the drawings.

Each spring is made of one continuous wire, and several of them are united by having the convolutions of each wire formed upon or embracing ties or rods of any suitable material.

a denotes the continuous wire, of which each spring is made, and *b* the rods or ties about which the convolutions of the wire are placed, and which serve to unite two or more parallel springs.

To make the spring I proceed as follows: Pins or wires of suitable size, and corresponding to the position of the rods *b* in the completed spring when not under stress, are fixed in location, and then the wire is wound around the pin denoted by *b*¹ from that to *b*², to *b*³, to *b*⁴, to *b*⁵, to *b*⁶, to *b*⁷, to *b*⁸, to *b*⁹, to *b*¹⁰, to *b*¹¹, and so on, until the wire is wound around each pin back and forth, upon the system indicated, until it terminates upon pin *b*²⁷ in the illustration.

The pins on which the wire is wound are a little larger in diameter than the rods to be used to connect a series of parallel springs, so that, after a series of springs has been formed by winding the wire upon the pins, the springs may then be slipped upon rods or ties *b*, of suitable length to receive any desired number of such springs, located parallel with each other and at uniform distances apart.

The springs may be kept from moving laterally on the rods or ties by driving brads or tacks into the rods *b*, if of wood, so as to prevent the wire *a* from moving sidewise; or, if rods *b* are of metal, they may have a projection or burr chipped up on either side of the wire *a*; or, as shown in the drawings, rubber sleeves *c* may be slipped upon the ties *b*, on each side of the wire *a*, said sleeves forming bunters to prevent noise when the upper parts of the spring are forced into contact with the lower parts, or strings or rope yarns may be woolded upon the ties on either side of the wire *a*.

Instead of using continuous ties *b*, the eyes formed in the wire *a* by its convolutions may be connected at the proper places by short pieces like rivets, and then a series of such springs may be united by cross-lines of any suitable material, which may, in some cases, be elastic or resilient.

Generally, it will be preferable to affix each spring, or some of an assemblage of such springs, to their supports or foundations.

This spring, through primarily intended for use in beds, may be employed in various other situations, where other forms of springs are now used.

These springs are easily and cheaply made of any desired length and to fill any space; for example, as a bed, or sofa bottom or back, several sections of springs may be made in length, as well as in breadth. This spring, or several of them combined into sections, may be combined with other forms of springs when desired, or my spring may be used to support other forms, or may be supported by them.

1 claim—

A compound spring made up of a series of springs formed from wire coiled and arranged to be united by rods or ties *b*, substantially as described.

JEREMIAH FISK.
